D19918

UNITED STATES PATENT OFFICE.

SAMUEL VICKERS, OF PHILADELPHIA, PENNSYLVANIA.

DESIGN FOR HOSEIERY.

SPECIFICATION forming part of Design No. 19,918, dated June 17, 1890.

Application filed May 24, 1890. Serial No. 353,096. Term of patent 7 years.

To all whom it may concern:

Be it known that I, SAMUEL VICKERS, a citizen of the United States, residing in the city and county of Philadelphia, State of Pennsylvania, have invented and produced a new and original Design for Hosiery, of which the following is a specification, reference being had to the accompanying photographic illustration, forming part thereof.

The leading feature of my design for hosiery is a plain band on the front thereof, extending from near the top over the instep toward the toe.

In the photograph, A designates the leg of a stocking, and B the foot thereof.

C designates a band, which extends along the front from near the top over the instep toward the toe.

At the top of the stocking, on the front thereof, is a rim D.

I claim—

A design for hosiery, as herein described and shown.

SAMUEL VICKERS.
